UNITED STATES PATENT OFFICE.

PAUL SZABO, OF SOUTH BEND, INDIANA.

DESIGN FOR A PICTURE-FRAME.

47,835.

Specification for Design. Patented Sept. 14, 1915.

Application filed June 22, 1915. Serial No. 35,691. Term of patent 7 years.

To all whom it may concern:

Be it known that I, PAUL SZABO, a subject of the King of Hungary, residing at South Bend, in the county of St. Joseph and State of Indiana, have invented a new, original, and ornamental Design for a Picture-Frame, of which the following is a specification, reference being had to the accompanying drawing, forming part thereof.

The figure is a front view of a picture frame, showing my new design.

I claim:

The ornamental design for a picture frame, as shown.

PAUL SZABO.
